KNITTED FABRIC AND ITS PRODUCTION

Harold Bestwick Hayto, London, and Wallace Blamire Mattinson, Spondon, near Derby, England, assignors to Celanese Corporation of America, a corporation of Delaware

Application August 8, 1939, Serial No. 288,998
In Great Britain August 17, 1938

9 Claims. (Cl. 66—195)

This invention relates to knitted fabrics and their production and is particularly concerned with the production of knitted fabrics having a high degree of elasticity by reason of a content therein of yarn made of or containing rubber, hereinafter referred to as "elastic" yarn.

According to the present invention an elastic knitted fabric is produced by warp-knitting a plurality of relatively inelastic yarns together with a number of interspersed elastic yarns or groups of yarns that are in an extended position, securing said elastic yarns in at least some of the courses of the fabric, and causing said elastic yarns to run in the fabric for substantial distances to and fro across the wales of the fabric, as well as across the courses of the fabric. Thus, the elastic yarns or groups of yarns may be caused to run alternately along the length of the fabric wale-wise and obliquely across it, or in a zig-zag manner. After the fabric is knitted in this manner the elastic yarns therein are caused or permitted to contract so that the fabric, as formed by the relatively inelastic yarns, buckles or cockles over its surface so as to produce an elastic knitted fabric, having a pleasing buckled effect. By reason of the fact that the elastic yarns are caused to run for substantial distances across the width of the fabric the contraction produced and the elasticity resulting are not limited to one direction of the fabric but extend in every direction.

The securing of the elastic yarns in the fabric may be effected by actually forming knitted loops in the elastic yarns, similar to those formed throughout the fabric in the inelastic yarns, or, alternatively or in addition, it may be effected by lapping, that is by securing the elastic yarn between the face of the fabric formed by the knitted loops of inelastic yarn, and the short floats of inelastic yarn that extend on the back of the fabric between the knitted loops on the face. In order to secure the elastic yarn by lapping in this manner, it is necessary that the elastic yarn and the float securing it should proceed, in the fabric, in different directions, e. g., one (usually the elastic yarn) along the length of the fabric and the other obliquely across the fabric, or both obliquely but in opposite directions across the fabric.

Several forms of fabric according to the invention will now be described in greater detail with reference to the accompanying drawings, in which

Figs. 1, 3, 5, 7 and 9 are large scale diagrams

showing in detail the movements of the elastic and inelastic threads during knitting, and

Figs. 2, 4, 6, 8 and 10 are small scale diagrams, corresponding respectively to Figs. 1, 3, 5, 7 and 9, showing generally the disposition of the elastic yarns in the fabric relatively to one another.

In order that the fabric should not be too heavy and that the elastic yarns employed should not interfere with one another so as to impede their own contraction, it is preferable that the elastic yarns or groups of yarns should be few in number relative to the inelastic yarns employed, and, should be distributed across the fabric. Furthermore, where the elastic yarns are knitted in at least some courses in order to anchor them in the fabric, it is preferable that the points at which they are so knitted should be relatively few in order that different knitted loops of the same yarn should not interfere with one another and prevent contraction.

The invention may be carried out on a warp-knitting machine, and while this machine may be a single bar machine in which all the yarns both elastic and inelastic partake of the same movements lengthwise of the machine during knitting, it is preferably a machine having two or more bars, and further preferable that the elastic yarns or groups of yarns should be fed to the machine in a bar or bars separate from the bar or bars employed to guide the relatively inelastic yarns.

Thus, for example, the invention may be carried out on a 3-bar machine of which the two front bars (i. e., the bars controlling the yarns that would appear on the face of the fabric) are threaded with inelastic yarn while the back bar is threaded with elastic yarn. With such an arrangement the elastic yarns may be caused to run for a short distance parallel to the length of the fabric, then for a short distance obliquely across the fabric, and as nearly at right angles to the length of the fabric as possible, then for a short distance parallel to the length of the fabric again, and then for a short distance obliquely across the fabric in the opposite direction.

Or again, two of the bars of a machine may be threaded with elastic yarn while the remaining bar or bars are threaded with inelastic yarns. This may be done for example on a four-bar machine in which the two remaining bars, e. g., the two front bars, knit the inelastic yarns, or it may be done on a three-bar machine in which the front bar only is threaded with inelastic yarns. In the latter case, however, it is desirable that the thread lapping movements of the single bar carrying the inelastic yarn should be substantial

in extent, e. g., of the order of six or more needle spaces, in order to avoid any tendency in the finished fabric to "split," a fault to which single bar warp knitted fabrics are liable when the guides have only a small range of thread lapping movements. By the use of two separate bars for the elastic yarns, different elastic yarns can be caused to move in different directions across or along the fabric at the same time. In this way, the elastic yarns may be caused to meet one another, and even to cross, so as to produce a pattern of closed or substantially closed figures such as hexagons, diamonds, or squares set with their diagonals along the length and across the width of the fabric.

When it is desired that the elastic yarns should proceed as nearly horizontal as possible across the fabric, provision may be made in the machine for rendering the presser (normally employed to close the beards of the knitting needles) inoperative for one, two or more courses so that a greater length of elastic yarn may be fed across the face of the fabric without the occurrence of complete knitting cycles on the inelastic yarns. A warp-knitting machine of the cut presser type may, for example, be adapted for this purpose, such a machine being provided with a plain presser as well as a cut presser, and with means for putting the plain presser into and out of operation as desired.

The elastic yarns employed for the purpose of the present invention may be fed under tension, whereby they are brought to the desired extended condition. Alternatively and preferably, however, the elastic yarns are treated while in an extended condition so as to fix them in that condition whereby they may be fed without tension or with merely a tension of the same order as that applied to the inelastic yarns employed. Thus for example a gum or size may be applied to the yarns while they are in the extended condition so as to hold them in that condition, the gum or size being subsequently removed by a suitable scouring or finishing operation on the knitted fabric.

The pattern effects produced by the configurations of the elastic thread in the fabric may be varied by varying the manner in which the guide bars carrying the elastic threads are moved or by varying the manner in which those guide bars are threaded with the elastic yarns. Thus, different sections across the width of the machine may be threaded in different manners so as to produce a different puckering effect. As an example of this one part of the fabric may be provided with twice as many elastic yarns as another part, whereby a closer pouching effect is produced over some parts of the fabric than over others.

Apart from any pattern effect that may appear from the configuration of the elastic thread in the fabric and the puckering and pouching effect resulting from the contraction thereof, any other convenient means available in connection with warped knitted fabrics may be resorted to for the production of pattern effects in the fabric. Thus the finished fabric or the yarns therein may be dyed and finished in any suitable manner. Where the fabrics are to be used for the making of bathing costumes, a water-repellent finish is especially useful. Again, where the fabric can conveniently be handled in a flat form, e. g., where elastic yarns are employed that have been fixed in an extended condition, the fabric may be printed before it is scoured to remove the gum

or size. Again, pattern effects may be produced by the use of different inelastic yarns, e. g., yarns made of different materials and/or dyed with different colours and/or having different degrees of lustre. Thus, yarns of different characteristics may be threaded in the guide bars in any desired grouping or manner of alternation, to produce stripes or zig-zags.

Furthermore, the pattern effects of these two kinds may be employed to enhance one another, the puckering of the fabric being caused to conceal, partly conceal or modify the pattern effects produced by other means, while when the fabric is extended, for example in wear, the said pattern effects are developed or restored to their original form.

The fabric shown in Figs. 1 and 2 is knitted on a 3-bar machine of 24-gauge, threaded with cellulose acetate yarns of 75 denier on the two front bars, there being in each bar one thread per needle of the machine. One thread of the front bar is indicated in Fig. 1 at 22 and one thread of the centre bar at 23. The back bar is threaded with elastic yarn having a content of sizing material which holds it in an extended condition, the denier of the yarn as extended being 400 and its denier in the unstretched state being 800. The elastic yarns are disposed in groups of two, one such group being indicated in Fig. 1 at 24, 25. There is one group of two to every 18 needles of the machine. The motions of the front bar may be represented by the figures 4-5, 1-0; each pair of numbers referring to the relative positions of the between-needle spaces through which the guides are moved in each course, first from rear to front of the needles and then from front to rear in order to produce lapping under the beard of the needle before the knitting of the course takes place. Similarly, the movements of the centre bar are represented by the figures 1-0, 1-2. Thus each of the front two bars continues to perform a two course cycle throughout the knitting operation. In the meantime the elastic yarns in the back bar perform the following extended cycle of movements, 0-0, 1-2, 5-6, 7-7, 9-9, 11-11, 13-13, 15-15, 17-17, 19-20; then 20-20, 21-21, repeated nine times; then 21-21, 20-19, 16-16, 14-14, 12-12, 10-10, 8-8, 6-6, 4-4, 2-1; then 0-0, 1-1, repeated nine times.

The yarns 22, 23, of the front and centre bars are shown broken away in order to show better the individual course of each yarn and also the course of the elastic yarns, one pair of which is indicated with thick lines at 24, 25. It will be seen that the elastic yarns 24, 25 proceed in zig-zag fashion up the fabric, passing alternately parallel to the length of the fabric and obliquely across the fabric. The elastic yarns are laid in wherever two numbers of the pairs of numbers indicating their motion are the same, being held in the fabric by the float of one or other of the yarns 22, 23, whichever is passing obliquely in a direction different from that in which the elastic yarn has passed. Thus the portion of elastic yarn indicated at 26 will be held in the fabric by the portion 27 of the yarn 22 and the portion 28 of the yarn 23. Where in the pairs of numbers indicating the motion of the elastic yarns the two numbers are different, i. e., at 1-2, 19-20, 20-19, and 2-1, the elastic yarn is looped or knitted. These points are indicated in Fig. 1 at 29.

Fig. 2 indicates the relationship of the pairs of elastic yarns to one another and it will be

seen that whereas the adjacent elastic yarns are only 14 wales apart, the lateral distance over which each extends across the fabric is equal to 20 wales so that the right-hand portion of the pair of elastic yarns indicated by 30 extends further to the right than the left-hand portion of the pair indicated at 31, and so on. It will be understood that Fig. 2 (as also Figs. 4, 6, 8 and 10) is a diagrammatic representation of the fabric in its stretched state and does not show the deformations due to the contraction of the elastic yarns. The oblique traversing of the elastic yarn across the fabric gives the fabric a considerable degree of elasticity across its width in addition to the elasticity given by both the vertical and the oblique parts of the elastic yarn along the length of the fabric.

The fabric shown in Figs. 3 and 4 is knitted on a 3-bar machine of 28 gauge in which the front bar is threaded with 100 denier cellulose acetate yarns, and performs the cycle of operations 2—3, 1—0, 3 times; 4—5, 4—3; then 5—6, 4—3, 3 times; 5—6, 2—1, 2—3, 1—0. The whole of this cycle is repeated while the centre and back bars make one cycle. The centre and back bars are threaded with elastic yarns similar to that used in the previous example but having an extended denier of 315 and an unstretched denier of 630. In each bar the elastic yarns are disposed in groups of two yarns separated by 3 empty guides, the groups being separated from each other by 23 empty guides so that there are two yarns to every 28 needles of the machine in each of the centre and back bars. The yarns of the centre bar make the following movements, 9—9, 10—10, 11—11, 12—12, 13—13, 14—14, 15—15, 17—17, 16—16, 16—16, 15—15, 14—14, 13—13, 12—12, 11—11, 10—10, 9—9, 8—8, 7—7, 6—6, 5—5, 4—4, 3—3, 2—2, 1—1, 0—0, 1—1, 1—1, 2—2, 3—3, 4—4, 4—4, 5—5, 6—6, 7—7, 8—8. The wales of the back bar perform the following movements, 9—9, 8—8, 7—7, 6—6, 5—5, 4—4, 4—4, 3—3, 2—2, 2—2, 1—1, 0—0, 1—1, 2—2, 3—3, 4—4, 5—5, 6—6, 7—7, 8—8, 9—9, 10—10, 11—11, 12—12, 13—13, 14—14, 15—15, 15—15, 16—16, 17—17, 15—15, 14—14, 13—13, 12—12, 11—11, 10—10.

It will be seen from these details that the two pairs of elastic yarns, indicated in Fig. 3 by the numerals 32, 33, cross one another at the point 34 so as to form a continuous diamond mesh. It will further be noted that each of the inelastic yarns, of which one is indicated by the numeral 35, covers a distance of 6 wales which reduces the tendency of the fabric to longitudinal splitting. Here the elastic yarns are secured in the fabric merely by lapping, which occurs whenever the inelastic yarn 35 is proceeding across the back of the fabric in a direction different from the direction in which the elastic yarn is proceeding. Thus at the points 36 on the elastic yarn the elastic yarn is secured by an inelastic yarn performing the movement indicated at the point 37 and similarly the elastic yarn at 38 is secured by inelastic yarn moving as at 39.

Fig. 4 shows the disposition of the different pairs of elastic yarn relatively to one another, the two pairs of yarns 32, 33 being shown in relation to the adjacent pairs 42, 43, each pair forming a chain of diamonds.

In Figs. 5 and 6 a more elaborate pattern is shown. In this case the three bars of the machine are threaded as described with reference to Figs. 3 and 4, but perform different movements. The front bar carrying the inelastic

yarns performs the following cycle, 2—3, 1—0, 3 times; 4—5; then 4—3, 5—6, 3 times; 4—3, 7—8; then 7—6, 8—9, 4 times; 5—4; then 5—6, 4—3, 3 times; 5—6, 2—1, 2—3, 1—0. The centre bar performs the movements 9—9, 10—10, 11—11, 12—12, 13—13, 14—14, 15—15, 17—17, 16—16; then 15—15, 4 times; then 16—16, 4 times; then 15—15, 4 times; then 16—16, 5 times; 15—15, 14—14, 13—13, 12—12, 11—11, 10—10, 9—9, 8—8, 7—7, 6—6, 5—5; then 4—4, 4—4, 3—3, 2—2; then 1—1, 4 times; then 2—2, 4 times; then 1—1, 5 times; 2—2, 3—3, 4—4, 4—4, 5—5, 6—6, 7—7, 8—8. The back bar performs the cycle 9—9, 8—8, 7—7, 6—6, 5—5; then 4—4, 4—4, 3—3, 2—2; then 1—1, 4 times; then 2—2, 4 times; then 1—1, 4 times; then 2—2, 5 times; 1—1, 0—0, 1—1, 2—2, 3—3, 4—4, 5—5, 6—6, 7—7, 8—8, 9—9, 10—10, 11—11, 12—12, 13—13, 14—14, 15—15; then 16—16, 4 times; then 15—15, 4 times; then 16—16, 4 times; then 15—15, 5 times; 16—16, 17—17, 15—15, 14—14, 13—13, 12—12, 11—11, 10—10.

In Fig. 5 one inelastic yarn is indicated by the thin line 44. A pair of yarns in the centre bar is indicated by the thick lines 45 and a pair of yarns in the back bar by the thick lines 46. To avoid longitudinal splitting the number of wales covered by each inelastic yarn is equal to nine. The elastic yarns form a continuous chain of hexagons, the pairs of yarns crossing at the points 47. The disposition of the successive chains of hexagons formed by the elastic yarns 45, 46, is shown in Fig. 6.

In Figs. 7 and 8 a fabric is shown of which the pattern is built up by uniting the pattern of the fabric shown in Figs. 3 and 4 with that of the fabric shown in Figs. 4 and 5. The bars are threaded in the same manner as for the fabric shown in Figs. 3—6 and the front bar performs the following motions, 2—3, 1—0, 2—3, 1—0, 2—3, 1—0, 4—5, 4—3; then 5—6, 4—3, 3 times; 5—6, 2—1; then 2—3, 1—0, 4 times; 4—5; then 4—3, 5—6, 3 times; 4—3, 7—8; then 7—6, 8—9, 4 times; 5—4; then 5—6, 4—3, 3 times; 5—6, 2—1, 2—3, 1—0. The centre bar performs the following motions 9—9, 10—10, 11—11, 12—12, 13—13, 14—14, 15—15, 17—17; 16—16, 16—16, 15—15, 14—14, 13—13, 12—12, 11—11, 10—10, 9—9, 8—8, 7—7, 6—6, 5—5, 4—4, 3—3, 2—2, 1—1, 0—0, 1—1; then 2—2, 4 times; then 1—1, 4 times; then 2—2, 4 times; then 1—1, 5 times; 2—2, 3—3, 4—4, 4—4, 5—5, 6—6, 7—7, 8—8. The back bar performs the following motions, 9—9, 8—8, 7—7, 6—6, 5—5; then 4—4, 4—4, 3—3, 2—2, 2—2, 1—1, 0—0, 1—1, 2—2, 3—3, 4—4, 5—5, 6—6, 7—7, 8—8, 9—9, 10—10, 11—11, 12—12, 13—13, 14—14, 15—15; then 16—16, 4 times; then 15—15, 4 times; then 16—16, 4 times; then 15—15, 5 times; 16—16, 17—17, 15—15, 14—14, 13—13, 12—12, 11—11, 10—10. These movements give a pattern of alternate diamonds and hexagons, the yarns 48 of the centre bar crossing the yarns 49 of the back bar as shown in Fig. 5 at the points marked 50. The inelastic yarn, of which one is indicated at 51 alternates between the movements of the yarns 35 of Fig. 3 and the yarns 44 of Fig. 5. The relative disposition of the successive chains of diamonds and hexagons is shown in Fig. 8 to be similar to that of the chains of hexagons shown in Fig. 6.

The fabric shown in Figs. 9 and 10 is knitted on a machine having a plain presser and means for putting it into and out of operation. A cut presser machine may be adapted for this purpose by using a cut presser that is completely cut

away, so that only the control of the plain presser is effective. As in the front and centre bars of the example described with reference to Figs. 1 and 2, the front and back bars are threaded with cellulose acetate yarn of 75 denier, one yarn to every needle in each bar, the elastic yarn in this case being fed by the centre bar. The centre bar is threaded with a single elastic yarn, of the same character as that described with reference to Figs. 1 and 2 to every twelve needles of the machine. The front bar performs the following cycle, 1-0, 1-2 six times; 1-0, 1-1, 1-1; then 1-2, 1-0 six times; 1-2, 1-1, 1-1. The back bar performs the following cycle, 1-2, 1-0, six times; 1-2, 1-1, 1-1; then 1-0, 1-2, six times; 1-0, 1-1, 1-1. It will be seen that the movements of the back bar (indicated in Fig. 9 by the thin line 52) are the same as those of the front bar (indicated at 53) except that when the front bar performs the movements 1-0 the back bar performs the movements 1-2 and vice versa. The centre bar (indicated by the thick line 54) performs the following movements, 14-14, 14-14, 14-14, 13-13, 13-13, 12-12, 13-13, 12-12, 13-13, 13-13, 13-13, 13-13, 14-14, 10-10, 5-5, 1-1, 1-1, 1-1, 2-2, 2-2, 3-3, 2-2, 3-3, 2-2, 2-2, 2-2, 2-2, 1-1, 5-5 10-10. In the course of this cycle the presser bar is put out of action for two courses on two separate occasions, i. e., on the two occasions, indicated at 55, 56, when both the front bar and the back bar are performing the movements 1-1, 1-1. It will be seen that during these movements no movement of the front and back bar threads across the needles takes place, the two figures of each pair being the same, and consequently no fabric is knitted. When the front and back bars are performing these movements on the first occasion and the presser is out of action, the centre bar, having at the last course performed the movements 14-14 is performing the movements 10-10, 5-5 and will proceed in the next course to perform the movements 1-1. As a result, in these four courses, in the second and third of which the presser is out of action, the elastic threads of the centre bar are moved from 14 to 1, a distance of thirteen needles. A similar effect is produced on the second occasion when the presser is put out of action and the centre bar, having performed the movements 1-1 performs the movements 5-5 and 10-10, 14-14 so as to return a distance of thirteen needles. On each occasion the two courses when the presser bar is put out of action allow time for the relatively stiff and intractable elastic yarn to run through the guides and to be led for the considerable distance requisite across the fabric.

As is indicated in Fig. 10 each elastic yarn at the extreme right of its movement, as at 57, is further to the right than the adjacent yarn on the right at the extreme left of its movement at 58. In this way there is produced a fabric having a very high degree of elasticity across its width as well as a substantial degree in the direction of its length.

The fabric produced in accordance with the present invention may be used in any circumstances in which an elastic knitted fabric having a puckered effect is desired. It is particularly useful for the manufacture of bathing costumes. For this purpose, the elasticity of the fabric in both directions enables it to conform readily to the figure of the wearer, so that no elaborate shaping is necessary in cutting out the fabric to make the garment.

Having described our invention, what we desire to secure by Letters Patent is:

1. Method of producing an elastic knitted fabric, said method comprising warp-knitting a plurality of relatively inelastic yarns together with a number of interspersed elastic yarns or groups of yarns that are in an extended condition and are guided in at least two sets during knitting, securing said elastic yarns in at least some of the courses of the fabric, and causing said elastic yarns to run in the fabric for substantial distances to and fro across the wales of the fabric as well as across the courses of the fabric, the yarns of each set being caused to run similarly in the fabric during knitting and the yarns of the different sets differently.
2. Method of producing an elastic knitted fabric, said method comprising warp-knitting a plurality of relatively inelastic yarns together with a number of interspersed elastic yarns or groups of yarns that are in an extended condition and are guided in at least two sets during knitting, securing said elastic yarns in at least some of the courses of the fabric, and causing said elastic yarns to run in the fabric for substantial distances to and fro across the wales of the fabric as well as across the courses of the fabric, the yarns of each set being caused to run similarly in the fabric during knitting and the yarns of the different sets differently.
3. Method of producing an elastic knitted fabric, said method comprising warp-knitting a plurality of relatively inelastic yarns together with a number of interspersed elastic yarns or groups of yarns that are in an extended condition and are guided in at least two sets during knitting, securing said elastic yarns in at least some of the courses of the fabric by forming said elastic yarns into knitted loops, and causing said elastic yarns to run in the fabric for substantial distances to and fro across the wales of the fabric as well as across the courses of the fabric, the yarns of each set being caused to run similarly in the fabric during knitting and the yarns of the different sets differently.
4. Method of producing an elastic knitted fabric, said method comprising warp-knitting a plurality of relatively inelastic yarns together with a number of interspersed elastic yarns or groups of yarns that are in an extended condition and are guided in at least two sets during knitting, securing said elastic yarns in at least some of the courses of the fabric, suspending knitting for short periods after said courses are knitted, causing said elastic yarns to run in the fabric in the course of said periods for substantial distances to and fro across the wales of the fabric and causing said elastic yarns to run across the courses of the fabric between said periods, the yarns of each set being caused to run similarly in the fabric during knitting and the yarns of the different sets differently.
5. Method of producing an elastic knitted fabric, said method comprising warp-knitting a plurality of relatively inelastic yarns together with a number of interspersed elastic yarns or groups of yarns that are in an extended condition and are guided in at least two sets during knitting, causing said inelastic yarns each to cover several wales of the fabric during the knitting of the fabric, securing said elastic yarns in at least some of the courses of the fabric, and causing said

elastic yarns to run in the fabric for substantial distances to and fro across the wales of the fabric as well as across the courses of the fabric, the yarns of each set being caused to run similarly in the fabric during knitting and the yarns of the different sets differently.

6. An elastic knitted fabric, comprising a plurality of relatively inelastic yarns warp-knitted to form a ground fabric together with a number of interspersed elastic yarns or groups of yarns that are secured in at least some of the courses of the fabric, said elastic yarns being in at least two sets, the yarns of each set being caused to run in the fabric in the same manner, and the yarns of the different sets in different manners, for substantial distances to and fro across the wales of the fabric as well as across the courses of the fabric.

7. An elastic knitted fabric, comprising a plurality of relatively inelastic yarns warp-knitted to form a ground fabric together with a number of interspersed elastic yarns or groups of yarns that are secured in at least some of the courses of the fabric, said elastic yarns being in at least two sets, the yarns of each set being caused to run in the fabric in the same manner for substantial distances to and fro across the wales of the fabric as well as across the courses of the fabric, the yarns in the different sets being caused to run in different manners and to cross one another repeatedly so as to form areas of fabric enclosed by elastic yarn.

8. An elastic knitted fabric, comprising a plurality of relatively inelastic yarns warp-knitted to form a ground fabric together with a number of interspersed elastic yarns or groups of yarns that are secured in at least some of the courses of the fabric by being formed into knitted loops in the fabric, said elastic yarns being in at least two sets, the yarns of each set being caused to run in the fabric in the same manner, and the yarns of the different sets in different manners, for substantial distances to and fro across the wales of the fabric as well as across the courses of the fabric.

9. An elastic knitted fabric, comprising a plurality of relatively inelastic yarns warp-knitted to form a ground fabric, each of said inelastic yarns covering several wales of the fabric, together with a number of interspersed elastic yarns or groups of yarns that are secured in at least some of the courses of the fabric and are caused to run in the fabric for substantial distances to and fro across the wales of the fabric as well as across the courses of the fabric, said elastic yarns being in at least two sets, the yarns of each set being caused to run in the fabric in the same manner and the yarns of the different sets in different manners.
